UNITED STATES PATENT OFFICE

2,470,212

WINDER BOBBIN

Gustav A. Carlson, Chicago, Ill., assignor to The
Boye Needle Company, Chicago, Ill., a corpora-
tion of Illinois

Application February 20, 1947, Serial No. 729,815

1 Claim. (Cl. 242—96)

1

This invention relates to a winder bobbin. It is particularly useful as a bobbin upon which yarn and the like may be wound and which may be used for making argyle socks, sweaters, etc.

An object of the invention is to provide a winder bobbin of novel construction upon which yarn and other material may be wound with facility and without causing a bunching of the yarn. Yet another object is to provide a bobbin of flat design with means for receiving yarn in such a manner as to prevent bunching thereof while, at the same time, providing means for facilitating the winding of the yarn into position. Other specific objects and advantages will appear as the specification proceeds.

The invention is illustrated, in a preferred embodiment, by the accompanying drawing, in which—

Figure 1 is a perspective view of a winder bobbin structure embodying my invention and containing yarn wound thereon; Fig. 2, a view similar to Fig. 1 but showing the yarn removed; Fig. 3, a top plan view; and Fig. 4, a longitudinal sectional view, the section being taken as indicated at line 4 of Fig. 3.

In the illustration given, 10 designates a bobbin body of flat sheet material having a half-moon segment cut away at 11 and having the end of the sheet adjacent the recess 11 provided with concave or inwardly turned walls 12. A slit 13 establishes communication between the recess provided by the inclined walls 12 and the recess 11. The inner edge of the recess 11 provides a substantially straight line 14.

The opposite end of the bobbin body 10 is also recessed to provide the outwardly extending arms 15 and 16. Between the inner ends of arms 15 and 16 there is a substantially straight edge 17 corresponding to the straight line 14 adjacent recess 11.

I find that the half-moon-like recess 11, with its straight wall 14 cooperating with the straight wall 17 of the opposite recess, is particularly useful in a device of this sort because the curved inner walls 18, bounding recess 11, aid in guiding the yarn toward either side along the straight edge 14. In the winding operation, when the yarn is drawn through the slit 13, it may be drawn laterally in either direction to cause the yarn to lie adjacent the selected side portion of the yarn receiving edge 14.

In the operation of the device, the winding of the yarn upon the bobbin provided by the straight lines 14 and 17 is facilitated with respect to the side 14 by the inwardly inclined walls 12

which direct the thread toward the slit 13. The yarn, as indicated by the numeral 19, is caused to be wound evenly upon the bobbin because of the two straight edges 14 and 17, the curved walls 18 of the recess 11 aiding in the guiding of the yarn toward either selected side. Instead of the yarn bunching toward the center of the surfaces 14 and 17, I find that it tends to spread along the straight lines 14 and 17 and, in the subsequent use of the yarn upon the bobbin in the making of argyle socks, sweaters, etc., the yarn unwinds readily without becoming caught between adjacent yarn threads.

The new structure is handled with great facility. On one end the recess is opened with the guide arms 15 and 16 extending rearwardly, while at the other end, which is closed to confine yarn upon the bobbin, the curved resilient walls on either side of the slit permit a substantially automatic opening of the slit as the yarn slips from the broad end of the body along the inclined walls 12 through the slit 13 and then laterally in either direction toward the wall 14.

The winder bobbin may be formed from a sheet of plastic material by cutting or stamping the same therefrom. For example, the bobbins may be struck from a sheet of plastic, casein, Celluloid, metal, cardboard, fiberboard, and the like. The device is preferably of substantially uniform thickness throughout and is preferably in the thin form indicated in the drawing.

In the structure described, there are in effect two pairs of arms, one pair at each end of the bobbin structure. The arms 15 and 16 provide an open recess between them and have their inner surfaces tapering rearwardly and outwardly. At the opposite end of the bobbin body, there are in effect two arms extending forwardly and then inwardly toward each other, meeting at the slit 13. These arms provide the closed recess 11. By reason of the resiliency of the plastic material from which the bobbin is made, the forward-extending arms flex readily adjacent the slit 13 to allow the inward movement of the yarn. Instead of having the arms meet, as indicated, at the slit 13, the arms may be spaced apart providing an opening therebetween.

While in the foregoing description, I have set forth one structure in great detail to illustrate one modification of the invention, it will be understood that such details may be varied widely by those skilled in the art without departing from the spirit of my invention.

I claim:

55. A winder bobbin, comprising a sheet body of

substantially uniform thickness in cross-section throughout, providing a core for the receiving and winding of thread, a pair of arms at one end thereof extending outwardly to provide a winding recess therebetween, said body providing a straight wall between said pair of arms, a pair of arms extending outwardly and toward each other from an opposite end of said core to provide therebetween a closed winding recess, said second pair of arms extending outwardly and then inwardly along an inclination toward each other, the outer edges of said second pair of arms forming a V-shaped thread-guiding surface with the point of the V at the meeting surfaces of said last-mentioned arms and inwardly directed toward said closed recess, the recess provided by

5

said arms being substantially half-moon shaped and providing a substantially straight wall at its inner side oppositely disposed to the straight wall provided between said first-mentioned pair of arms.

GUSTAV A. CARLSON.
